UNITED STATES PATENT OFFICE.

SIMEON D. KING, OF ROLLING PRAIRIE, INDIANA.

PORTFOLIO.

SPECIFICATION forming part of Letters Patent No. 326,750, dated September 22, 1885.

Application filed July 11, 1885. (No model.)

To all whom it may concern:

Be it known that I, SIMEON D. KING, a citizen of the United States, and a resident of Rolling Prairie, in the county of La Porte and State of Indiana, have invented certain new and useful Improvements in Assessors' Cases; and I do hereby declare that the following is a full, clear, and exact description of the invention, which will enable others skilled in the art to 5 which it appertains to make and use the same, reference being had to the accompanying drawings, which form a part of this specification, and in which—

Figure 1 is a perspective view of my improved 15 portable desk and case, showing it closed. Fig. 2 is a similar view of the same open, and Fig. 3 is a sectional view on line $\times \times$, Fig. 1.

Similar letters of reference indicate corresponding parts in all the figures.

20 My invention has relation to portable writing-desks and blank-holding cases; and it consists in the improved construction and combination of parts of a desk and blank-holding case especially adapted for the use of assessors, census-takers, canvassers, or any other persons having to write in the open air or at 25 places where a desk or table is not accessible, as hereinafter more fully described and claimed.

30 In the accompanying drawings, the letter A indicates a board having a frame, B, around its edges projecting at both sides of the board, which is rectangular and of the same size as the blanks desired to be held in the case.

35 Two pairs of elastic bands, C C, are stretched across the frame near the ends of the same, and serve to retain the blanks, which are placed in the recesses formed at both sides of the board by the raised frame surrounding the 40 board. A rectangular piece, D, of canvas, oil-cloth, leather, or other similar material is secured at its middle to one side piece of the frame, and forms two flaps, E E, which cover the recesses in the frame and protect the blanks contained in the recesses. The outer edges of 45 these flaps are provided with straps F, having eyes G, which may be buttoned over knobs or buttons H upon the side piece of the frame, and one of the side pieces of the frame is pro-

vided with a handle, I, by means of which the 5 contrivance may be easily and conveniently carried.

When the device is to be used, the flaps may be opened, when the blanks will be found contained in the recesses, where they will be continually kept in their regular order, as they were placed there, and the person using the device may now proceed to fill out the blanks, resting the desk against any object, the board giving him a level surface, and the blanks will 6 be prevented from being blown away by the wind by the elastic straps confining their ends within the recesses in the frame. The raised frame surrounding the blanks will keep them straight, and will prevent the edges from being torn ragged or soiled, as well as it will confine the blanks when the device is carried from one place to another.

If desired, one or more of the sides of the frame may be recessed, so as to receive an ink-bottle capable of being closed, pens, or other writing material, and the board, frame, and flaps may be of any suitable material, and be ornamented in any desired manner, according to the taste or fancy of the maker or user.

Having thus described my invention, I claim and desire to secure by Letters Patent of the United States—

In a portable writing-desk, the combination of a rectangular board, a frame secured around the edges of the board and projecting at both sides of the board, elastic straps passing from two side pieces of the frame across both sides of the board near the ends, a rectangular piece of flexible material secured at its middle to one side of the frame, forming flaps covering the sides of the board, and having perforated straps at their free edges for buttoning on buttons upon the side of the frame, and a handle secured to one side of the frame, as and for the purpose shown and set forth.

In testimony that I claim the foregoing as my own I have hereunto affixed my signature in presence of two witnesses.

SIMEON D. KING.
